US00D631042S

(12) **United States Design Patent**
Chen

(10) **Patent No.:** **US D631,042 S**
(45) **Date of Patent:** **** Jan. 18, 2011**

(54) **ALL IN ONE COMPUTER**

(75) Inventor: **Yun-Lung Chen**, Taipei Hsien (TW)

(73) Assignee: **Hon Hai Precision Industry Co., Ltd.**,
Tu-Cheng, Taipei Hsien (TW)

(**) Term: **14 Years**

(21) Appl. No.: **29/368,982**

(22) Filed: **Aug. 31, 2010**

(30) **Foreign Application Priority Data**

Jun. 17, 2010 (CN) 2010 3 0104754

(51) **LOC (9) Cl.** **14-02**

(52) **U.S. Cl.** **D14/337; D14/371**

(58) **Field of Classification Search** D14/371-376,
D14/125-129, 336, 337; 248/917-924, 122.1,

(57) **CLAIM**

The ornamental design for an all in one computer, as shown and described.

DESCRIPTION

FIG. 1 is a perspective view of an all in one computer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view thereof; and,

FIG. 9 is a perspective view thereof shown in an alternate folded position for use.
